DOCUMENT CASE

Paul D. Barrett, San Francisco, Calif., assignor
of one-half to Lois B. Crown, Washington, D. C.

Application January 31, 1940, Serial No. 316,567

1 Claim. (Cl. 312—112)

My invention relates to means for receiving and storing in order flat papers, documents, pamphlets, charts, maps and the like, and is concerned especially with such a document case which will occupy a very small space when not in use, yet which is effective to present any of the contained documents readily for use and which likewise will serve as a work table on which such documents, maps, papers and the like can be spread for reference.

An object of my invention is to provide a document case which is readily fabricated and which is relatively inexpensive.

Another object of my invention is in general to improve document cases.

In its preferred form, the document case of my invention includes a baseboard adapted to be secured to an upright, such as a wall, and being provided with a ledge. Hingedly mounted with respect to the baseboard is a cover which is substantially coextensive with the baseboard and is adapted to move from closed position against the baseboard to open position at an angle to the baseboard in which position it is retained by support means such as chains, the cover being surrounded by side boards with which co-operate means for urging the contained maps, documents and the like against the cover for permanent positioning.

In the drawing:

Fig. 1 is a perspective of the document case of my invention in open position, showing various documents in position in the interior thereof; and

Fig. 2 is a perspective, on a slightly smaller scale, showing the document case of my invention in closed position.

Although the document case of my invention is susceptible of utilization under many different circumstances and in a variety of environments, it is ordinarily exceedingly useful inside a room having a sufficiently substantial wall so that there can be mounted thereon and secured thereto, either temporarily or permanently, a baseboard 6. This baseboard can be fabricated of appropriate material, and conveniently is of wood, finished in an appropriate manner to harmonize with its surroundings.

Along the upper edge of the baseboard 6 there is secured an overhanging ledge 7 adjacent which in its closed position a cover 8 is adapted to be disposed. The cover is preferably movable with respect to the baseboard 6 between a closed position and an open position, and is suitably fastened for such movement by means of

5 a plurality of hinges 9 parts of which are secured to the baseboard 6 and the other parts of which are preferably secured to one side wall 11 of a plurality of such side walls 12, 13 and 14 which are disposed on the marginal edges of the cover 8.

To hold the cover in an established open position and preferably in substantially a horizontal plane, there is secured to the baseboard 6 a pair 10 of supporting chains 16 and 17 which are also secured to the side wall 12 and which are so located as to be disposed within the compartment defined by the baseboard 6, the cover 8 and all of the side walls 11, 12, 13 and 14 when 15 the cover is in closed position. In such closed position the cover is temporarily retained by a pair of fasteners 18 and can be locked by a padlock 19 engaging a suitable pair of fastenings 21 secured to the ledge 7 and the side wall 20 13 respectively.

In order to retain documents and comparable material within the compartment when the structure is closed, and in order that they will not be unduly dislodged when it is being opened 25 and is retained in open position, I provide a plurality of retaining means. Spanning the side walls 13 and 14 adjacent the side wall 7 is a panel 23 which extends part way toward the side wall 12 and in effect forms a pocket 24 within which 30 material can be inserted. On the side walls 13 and 14 I provide a pair of wedges 26 with which co-operate cams 27 located at the opposite ends of a bar 28 of sufficient length to span the cover and adapted to be pressed or urged toward the 35 interior of the cover 8 so as to clamp papers and documents therebetween firmly in position, the co-operation of the cams 27 and the wedges 26 serving to accommodate papers and documents of different thicknesses and sizes.

40 In addition to the foregoing, I provide clamp-
ing means constituted by a pair of plates 31 and 32 which are substantially identical so that but one need be described. The plate 31, for example, is a rectangular member connected by a 45 pair of hinges 33 to the side wall 12 and adapted in one position to lie immediately over any docu-
ment or documents on the cover 8. To retain the plate 31 in such closed position, and also to retain it in open position as shown by the plate 32 in Fig. 1, I provide a pair of springs 34 and 36. Each of the springs 34 and 36 is at one end connected to one of two staples 37 located adjacent the free end of the plate 31 and at the other end fas-
tened on the opposite side of the axis of the 50 55

hinges 33 by a suitable fastening (not shown) in a recess 38 cut in the side wall 12. This location of the springs 34 and 36 is effective to urge the plate 31 against material between such plate and the cover 8, but when the plate 31 is in open position, as is indicated by plate 32 in Fig. 1, the springs 34 and 36 pass the axis of the hinges 33 and are then effective to retain the plate in open position.

In the use of this document case, ordinarily it is in closed position as shown in Fig. 2, and the contents are available when the closures 18 are operated and the lock 19 is opened. At that time the cover 8 moves downwardly into its horizontal position as shown in Fig. 1, being supported by the hinges 9 and the chains 16 and 17. The various documents which are positioned therein are held either within the pocket 24 or

5 by the bar 28 or by the leaves 31 and 32. Upon release of these members, or the appropriate one or ones of them, the documents can be removed and can be spread upon the table formed by the interior of the cover 8 for perusal.

I claim:

A document case comprising an upstanding baseboard, a ledge extending along the top thereof, a cover, side walls upstanding from the margins of said cover, hinges connecting one of said side walls and said baseboard, fasteners for holding another of said side walls adjacent said ledge, wedges on remaining ones of said side walls, a bar extending across said cover, and cams on said bar for engaging said wedges to force said bar against said cover when advanced.

PAUL D. BARRETT.
